UNITED STATES PATENT OFFICE.

HENRY E. MOFFAT, OF HIGHLAND PARK, MICHIGAN.

COMBINED OIL EXTRACTOR AND CONDENSATE RECEIVER.

Application filed March 26, 1926. Serial No. 97,812.

This invention relates to combined oil extractors and condensate receivers.

It is the object of the invention to provide an apparatus for receiving the exhaust steam of engines or any steam contaminated by lubricating or other oil, and to remove the impurities and to also collect in said apparatus any condensed portion of said steam.

Another object is to provide an apparatus of the specified character that will be provided with outlets for accumulated oil and water, and which will make provision against any overflow of oil or water into the steam inlet pipe in case of an abnormal rise of the levels of the oil and water.

These and various other objects the invention attains by the construction hereinafter described and illustrated in the accompanying drawing, wherein:

Figure 1 is a view of the improved apparatus in perspective cross section.

Figure 2 is a horizontal sectional view of the same on line 2—2 of Figure 1.

Figure 3 is a detail vertical sectional view of a vacuum breaker used in the invention, the section being taken upon the line 3—3 of Figure 2.

In these views the reference character 1 designates a drum or casing former preferably of boiler plate or sheet metal, and having pipes 2 and 3 opening substantially centrally thereinto through its top and bottom for respectively delivering contaminated steam and for withdrawing purified steam. The cylindrical side wall of the drum 1 may be extended above said drum, as shown in Figure 1, to form a tank 3^a surrounding the pipe 3 containing water to be heated by the steam rising through the pipe 3.

Within the drum 1 and secured to the bottom thereof in spaced relation to its side wall and top is an inner drum 4 concentric with the outer drum, and a partition 5 horizontally arranged in said inner drum divides the same into upper and lower steam expansion compartments. 6 designates an extension of the inlet pipe 2 which passes through the lower compartment of the inner drum, and opens into the upper compartment thereof, thus adapting the incoming steam to initially enter said upper chamber. The partition 5 is formed with a plurality of ports 7 through which the steam discharges from the upper to the lower chamber of the inner drum, and preferably col-

lars 8 are secured to the under side of said partition surrounding the openings 7, said collars projecting at their lower ends into the upper ends of larger collars 9 secured to the floor of the drum 1. The steam escaping downwardly through the collars 8 from the upper to the lower compartment of the inner drum, is required to reverse its direction of flow in passing between the collars 8 and 9 into the lower compartment, and there results from this reversal of flow, a tendency to throw out of suspension any oil or water that may be entrained by the steam. The liquids thus separated, escape from the collars 9 through a series of openings 10 in the lower portions of said collars to the main area of the lower compartment.

From the lower compartment of the inner drum, the steam escapes to the annular space 75 surrounding the inner drum through a circular series of ports 11 in the wall of the inner drum, and from said space, the steam flows across the top of the inner drum to the outlet pipe 3.

It is preferred to secure to the outer portion of the partition 5 the depending ring 11^a spaced at its lower end from the bottom of the drums 1 and 4, and arranged between the outer wall of the drum 4 and the series 85 of collars 8 and 9. This baffle ring is encountered by the steam outwardly flowing between the collars 8 and 9 and deflects the flow of such steam downwardly. As the direction of this flow is thus abruptly changed, 90 a further tendency is created to deposit on the wall of said baffle member any condensed globules of water or oil that may be still carried by the steam.

Expansion of the steam in the outer portion of the drum 1 tends to precipitate out any condensate still carried by the steam. 12 designates an outlet pipe communicating with the drum 1 through the bottom thereof for carrying off water of condensation, and 100 13 indicates an oil outlet pipe which is connected with the lower compartment of the inner drum through the floor thereof, the oil accumulating in said compartment being under normal conditions discharged through 105 said pipe. 13^a designates a blow off opening.

One or more vacuum breakers, each comprising a pipe 14 passing through the cylindrical wall of the drum, and a normally 110 closed check valve 15 upon the outer end of said pipe, serve to admit outside air to

the drum, in case the pressure therein becomes sub-atmospheric. In order that said vacuum breakers may act immediately to overcome any vacuum tendency arising either in the outer or inner drum, the pipes 14 are arranged in the horizontal plane of the ports 11 and have their inner ends only a slight distance from said ports.

In the event that the pipe 13 becomes clogged with sediment or for any other reason fails to properly function, the level of oil and water in the bottom portion of the apparatus will rise until an overflow occurs through the ports 11 into the outer drum, the overflowing liquids discharging from the outer drum by way of the pipe 12. Also if the pipe 12 for any reason becomes blocked, the resulting accumulation of water of condensation in the outer drum will overflow through the ports 11 into the inner drum, and will be carried off by the oil outlet pipe 13. Thus, it is to be noted that the arrangement prevents any overflow of the liquids into the steam supply pipe. It is highly essential to avoid such an overflow since if the pipe 2 leads from the exhaust ports of engines as is usually the case, such liquids may find entrance to the engine cylinders and cause cracking or bursting of said cylinders.

It is to be understood that the entire space within the drums 1 and 4 provides for an expansion of the steam entering the apparatus and a retardation of the steam velocity, and that such expansion and retardation are useful in facilitating precipitation of any impurities carried by the steam.

What I claim is:

1. In a device of the character described, a drum having a steam outlet, a smaller drum within the first named drum, a partition dividing the smaller drum into two compartments, means for delivering steam to one of said compartments, said partition having an opening for the passage of steam to the other compartment, and means in the last named compartment for baffling the steam to precipitate liquid particles therefrom, the inner drum being formed with an opening from the last named compartment into the outer drum for the flow of steam.

2. In a device of the character described, a cylindrical drum having a steam outlet, a smaller cylindrical drum centrally arranged within the first named drum, a partition dividing the smaller drum into two compartments, baffle means in one of said compartments, means for delivering steam to the other of said compartments, said partition having an opening for the passage of steam to the baffle compartment, the inner drum having a circular series of openings in its cylindrical wall providing for a flow of steam from the baffle compartment to the outer drum.

3. In a device of the character described, a drum having a steam outlet, a smaller drum within the first named drum, a partition dividing the smaller drum into two compartments, one of which forms a baffle chamber, means for delivering steam to the other of said compartments, said partition having a plurality of openings for the flow of steam to the baffle compartments, collars carried by said partition in the baffle compartment, and surrounding said openings, larger collars projecting from a wall of the baffle compartment, and spaced at their free ends around the free ends of the first mentioned collars, the inner drum being formed with an opening for the discharge of steam from the baffle chamber to the outer drum.

4. In a device of the character described, a drum, a partition dividing said drum into upper and lower compartments, means for delivering steam to the upper compartment, said partition having an opening for the flow of steam to the lower compartment, a baffle arranged in the lower compartment encountered by the steam for producing a precipitation of liquid particles from the steam, said drum having a steam outlet from said lower compartment, and a member co-acting with said drum to form a steam expansion chamber receiving steam from said lower compartment, said member having a steam outlet.

5. In a device of the character described, a drum, a partition dividing said drum into an upper and lower compartment, means passing through the lower compartment for delivering steam to the upper compartment, said partition having an opening for the discharge of steam to the lower compartment and said drum having an opening for the outflow of steam from the lower compartment, baffle means encountered by the steam in the lower compartment for effecting a precipitation of liquid particles, and a member co-acting with said drum to form an expansion chamber receiving steam from the lower compartment, said member having a steam outlet.

6. In a device of the character described, a drum, a partition dividing said drum into an upper and a lower compartment, means for delivering steam to the upper compartment, said partition having a plurality of openings for the flow of steam to the lower compartment, annular baffle members carried by said partition surrounding said openings thereof within the lower compartment, and co-acting annular baffle members carried by the bottom of said drum and spaced at their lower ends from the lower ends of the first named baffle members, said drum having a series of outlets in its outer wall, and a baffle ring within the said lower compartment between said annular baffle members and outlets.

7. In a device of the character described, a drum, a partition dividing said drum into upper and lower compartments, means for delivering steam to the upper compartment, said partition being formed with a plurality of openings for the flow of steam to the lower compartment, baffle members arranged in the lower compartment adjacent to said openings, and a baffle ring depending from said partition in the lower compartment extending around said baffle members, the outer wall of said drum being formed with a plurality of outlets from the lower compartment.
- 15 8. In a device of the character described,

a drum having a steam outlet, a smaller drum within the first named drum, means for delivering steam to the inner drum, means within the inner drum for baffling the steam and separating oil therefrom, the inner drum having an outlet in its peripheral wall for the discharge of steam into the outer drum, and a vacuum breaker mounted in the wall of the outer drum and opening within said drum in proximity to said steam outlet of the inner drum.

In testimony whereof I sign this specification.

HENRY E. MOFFAT.
